UNITED STATES PATENT OFFICE.

PAUL MAKRAY, OF CHICAGO, ILLINOIS.

TOY.

1,259,542.

Specification of Letters Patent. Patented Mar. 19, 1918.

Application filed February 23, 1917. Serial No. 150,507.

To all whom it may concern:

Be it known that I, PAUL MAKRAY, a subject of the Emperor of Austria-Hungary, who have declared my intention of becoming 5 a citizen of the United States, and a resident of the city of Chicago, county of Cook, and State of Illinois, have invented certain new and useful Improvements in Toys, of which the following is a specification.

10 My invention relates to improvements in toys, and more especially to toy bowling alleys, the object of the invention being to provide a simple and efficient toy of this character which may be readily folded into compact form.

15 The invention consists in the combinations and arrangements of parts hereinafter described and claimed.

The invention will be best understood by 20 reference to the accompanying drawings forming a part of this specification, and in which,

Figure 1 is a top plan view of a toy embodying my invention,

25 Fig. 2, a longitudinal section of the same,

Fig. 3, a bottom plan view of the same with portions broken away for the sake of clearness,

30 Fig. 4, a longitudinal section taken through a toy gun or projector employed in the construction,

Fig. 5, an end view of said projector, and

Fig. 6, a view of the toy folded into compact form.

35 The preferred form of construction as illustrated in the drawings comprises a game board made up of two sections 7 and 8 hingedly connected together by means of hinges 9 on the bottom thereof so as to fold down- 40 wardly. The board sections 7 and 8 are provided with side boards 10 constituting a miniature bowling alley, and suitable supporting legs are arranged at the front and rear thereof.

45 A set of miniature bowling pins 12 are arranged at the rear of the game board and are connected at their bottoms with branch cords 13 extending through perforations in the pin "spots" and connected with an operating cord 14 extending to the front of the 50 toy where it is connected with an operating lever 15. A casing 16 incloses the branch cords 13 to protect the same.

A toy gun or projector 17 is arranged at 55 the front end of the board, said projector being equipped with a spring held plunger

18 operable by means of a setting lever 19 and controlled by a trigger 20 adapted to engage a notch 21 therein. A ball receptacle or hopper 22 is positioned on the projector 17 and is adapted to contain a plurality of balls 23 automatically fed by gravity, one at a time, into the projector 17 upon reciprocation of the plunger 18, as will be readily understood. A cotter pin 24 is passed 60 through the muzzle end of the projector 17 and is attached thereto by means of a cord 25, said pin serving to retain the balls in the projector when desired.

The projector is mounted on the board 70 portion 7 by means of a hinge 26, one leaf of said hinge being secured to the bottom of said projector and the other leaf 27 of said hinge being pivoted by means of a screw 28 to the board 7, the arrangement being such 75 that the projector 17 may be oscillated laterally to project the balls to any desired portion of the rear end of the bowling alley and may be readily folded flat when not in use. A segmental rest 29 is provided for the 80 muzzle end of the projector 17.

By this arrangement an ordinary game of ten pins may be played on the board and the pins 12 readily reset when desired. Also the board may be readily folded into compact 85 form for shipment or otherwise, as indicated in Fig. 6.

While I have illustrated and described the preferred form of construction for carrying 90 my invention into effect, this is capable of variation and modification without departing from the spirit of the invention. I, therefore, do not wish to be limited to the precise details of construction set forth, but desire to avail myself of such variations and 95 modifications as come within the scope of the appended claims.

Having described my invention what I claim as new and desire to secure by Letters Patent is:

1. A game board and a projector therefor, said projector being hingedly mounted on said board to fold thereagainst and pivoted to oscillate laterally with respect to said board, substantially as described.

2. A game board; a hinge member having one leaf pivoted to said board to oscillate therein; and a projector secured to the other leaf of said hinge member to fold against said board, substantially as described.

3. A device of the class described comprising a foldable game board consisting of two

parts hinged together centrally to fold downwardly; side boards on said game board; supporting legs at each end of said board; a hinge member having one leaf pivoted to said board to oscillate therein; and a projector secured to the other leaf of said hinge member to fold against said board, substantially as described.

In testimony whereof I have signed my name to this specification in the presence of 10 two subscribing witnesses.

PAUL MAKRAY.
